UNITED STATES PATENT OFFICE.

RICHARD C. H. SIEWERTS, OF HAMBURG, GERMANY, ASSIGNOR TO THE FIRM OF JULIUS HARDT, OF HAMBURG, GERMANY.

INCANDESCENT GAS-BURNER.

SPECIFICATION forming part of Letters Patent No. 743,339, dated November 3, 1903.

Application filed December 30, 1901. Serial No. 87,798. (No model.)

To all whom it may concern:

Be it known that I, RICHARD C. H. SIEWERTS, a subject of the German Emperor, and a resident of Hamburg, in the German Empire, have invented certain new and useful Improvements in Incandescent Gas-Burners, of which the following is a specification.

This invention relates to an improved construction of gas-burner for use with an incandescent mantle, whereby finely-divided streams or jets of an intimate mixture of gas and air are caused to issue radially in horizontal direction from the periphery of the burner-head, and thus produce a flame of such a ball or bulb shaped form as to be, in contradistinction to the form of the flames of incandescent gas-burners of well-known construction, of a greater diameter and in contact with a larger portion of the surface of the incandescent mantle, thereby effecting the possibly greatest amount of illumination.

With this end in view my invention consists in certain novel features of construction and combinations of parts, as will be herein-after fully described with reference to the accompanying drawing, in which I have shown a vertical central section of a preferred form of my improved incandescent gas-burner embodying my invention.

30 The upper end *a* of the socket *a'*, with which the gallery *a²* is placed upon the gas-supply tube *b*, provided in well-known manner with air-supply orifices *b'*, is shouldered or enlarged so as to form with a socket or ring *c*, 35 screwed upon or otherwise attached to the enlarged end *a*, a mixing-chamber of greater diameter than the supply-tube *b*. The upper part or top of this mixing-chamber is constituted by a solid circular plate or disk *d*, supported by a perforated conical socket *d'*, the latter and the solid disk *d* being constructed and united so as to form an inverted cup having a flaring or tapering wall and being held in position upon the upper rim of the enlargement *a* by means of the socket or ring *c*, as this is obvious from the drawing without further detailed explanation. The inverted cup *d d'* is arranged to overtop the socket or ring *c*, so that the disk *d* is a certain distance apart 45 and above the upper rim of the socket or ring

c, whereby a lateral annular outlet-passage for the gas and air mixture is formed between the disk *d* and the socket or ring *c*. Just below the disk *d* the perforated outwardly-tapering wall *d'* is provided with a strongly-marked contracture or shoulder *d²*, and it is this shoulder in combination with the laterally-projecting edge of the disk *d* which in consequence of their peculiar influence upon the issuing gas and air mixture form the most 60 essential features of my invention, as will be explained later on.

The plate *d* has a recess or socket *e* for the support of the mantle-rod *f*. The dotted line *g* indicates the mantle, and the dotted line *h* 65 a dome-shaped wire-gauze suitably fastened or clamped within the interior of the inverted cup *d d' d²*.

The function of my improved incandescent gas-burner is as follows: The gas and air mixture striking in its upward flow against the disk *d* is deflected and caused to issue radially in or about in horizontal direction through the perforations just below the deflecting-disk *d*. The protruding edge of the latter, which overlaps or projects over the contracture or shoulder *d²*, acts at the same time as a guide for the issuing jets of the gas mixture and assists such jets to continue their radial outward flow in chiefly a horizontal direction. The draft of external air entering into the chimney from below bends the horizontal gas-mixture jets, or, rather, horizontal veil of such gas mixture, upward, and thus a flame is produced of a bulb shape, 85 such as to be in contact with a considerably large portion of the surface of the incandescent mantle, and consequently produce a highly-increased illuminating effect.

Having thus described my invention, what 90 I claim as new therein, and desire to secure by Letters Patent, is—

1. A burner comprising a gas and air supply tube, a mixing-chamber, an element seated on the latter and having a perforated flaring upper portion, and a disk covering said upper portion, for the purpose set forth. 95

2. A burner comprising a gas and air supply tube, a mixing-chamber at the outlet, a converging element seated on the mixing- 100

chamber and having a perforated flaring upper portion, and a disk covering said upper portion, for the purpose set forth.

3. A burner comprising a gas and air supply tube, a mixing-chamber at the outlet thereof, a sleeve surrounding the latter, a converging element having a flaring upper portion, and a solid disk covering said flaring portion and seated on the chamber with-
5 in the sleeve, and ports formed in said flar-
ing portion parallel to the plane of the disk,
for the purpose set forth.

4. A burner comprising a gas and air supply tube, a mixing-chamber at the outlet thereof, a sleeve fitted to the chamber, a con-
verging element and deflecting-disk above
the chamber, the said converging element
and sleeve forming between them a circular
gas-passage substantially V-shaped in cross-
section, substantially as set forth.

RICHARD C. H. SIEWERTS.
